UNITED STATES PATENT OFFICE.

EUGENE A. KUEN, OF CINCINNATI, OHIO, ASSIGNOR TO THE THOS. J. CORCORAN LAMP COMPANY, OF CINCINNATI, OHIO, A CORPORATION OF OHIO.

AUTOMOBILE LAMP CLOSURE FASTENER.

Application filed October 21, 1924. Serial No. 745,021.

This invention relates particularly to an automobile lamp closure fastener in which objects have been to produce a closure fastener which embodies the utmost simplicity of manufacture, number of pieces employed, of assembly, and of operation both in the acts of fastening and unfastening as well as in the functioning of the fastener when the closure is mounted properly in position.

These and other objects are attained in the fastener described in the following specification and illustrated in the accompanying drawings, in which:

Fig. 1 is a sectional view of a lamp having a closure embodying my invention, attached thereto.

Fig. 2 is a fragmental perspective view of a detail of the construction shown in Fig. 1.

Fig. 3 is a fragmental perspective view of a detail of construction which is used in cooperation with that shown in Fig. 2.

Fig. 4 is a fragmental front elevation of the lamp body with the closure glass in position, showing the novel features of my invention.

Fig. 5 is a view similar to Fig. 1, but showing a slightly modified form of my invention.

Fig. 6 is a view similar to Fig. 2, but of the embodiment shown in Fig. 5.

Fig. 7 is a view similar to Fig. 3, but of the embodiment shown in Fig. 5.

Fig. 8 is a view of a further modified form of lamp fastener.

Figs. 9 and 10 are fragmental perspective views showing details of the form shown in Fig. 8.

I will first describe the form of the invention as shown in Figs. 1 to 4 inclusive. In the showing of this form, as in the others described herein, the usual type of automobile head lamp body and closure is disclosed. The body 11 is formed with a flange 12 upon which is seated the flange 13 of the usual reflector 14. Closing the mouth of the reflector is the usual plain glass or lens 15, which is retained in place snugly by the closure rim 16. The usual lamp bulb 17 and connector assembly 18 are employed, with the ordinary form of focusing device 19 for obtaining focusing adjustment of the bulb.

I prefer showing my invention as used in connection with a closure rim having a rear edge which is turned inwardly and forwardly to form a hooked annular edge 17'.

In the wall of the body, adjacent to its open end is located an opening 20, and in alignment with it is another opening 21 formed in the flange 12. The reflector rim 13 is provided with a notch in register with opening 21 so as to leave the opening 21 unobstructed. The device which I employ as a fastening element 22 is merely a strip of spring material such as phosphor bronze. The strip is bent into a generally U-shaped formation having the ends suitably formed to perform the function intended. This end formation takes different shapes. In the incorporation of my invention I prefer to employ two spring elements with each lamp body, one being located at the top of the body and one at the bottom. The ends of the top spring element are formed by bending them away from one another and at a substantial right angle to the legs of the U. One end 23 is adapted to pass through the opening 20 and is provided with a slot 24 which engages a tongue 25 extending partially across opening 20. This end 23 is adapted to engage the hooked rear edge 17' of the closure rim. The forwardly extending end 26 of the element 22 is turned slightly inwardly and then outwardly so that when it is passed through opening 21 in the body flange it will have to be pressed and will snap into position. This formation is utilized to retain the reflector in position by engaging its rim within the notch which registers with opening 21 of the body.

The bottom fastening element is substantially the duplicate of the top fastening element. The forward reflector holding end 26 is identical, but the end 27 which is held by the body wall is materially thicker and is provided with a screw threaded aperture 28. Also instead of turning rearwardly, the end 27 is turned straight out radially. Cooperating with this end is a lug 29 extending from the closure rim. Through this lug and into screw threaded end 27 is passed a screw 30, a spacing collar 31 being provided to prevent too much tension being placed on the fastener for the proper setting of the closure rim.

In fastening the closure in position, it is necessary to hold the closure rim outwardly from the bottom and to bring the top portion of the hooked edge into engagement with the end 23 of the element 22. The rim is then moved toward the body until the

screw 30 will engage the aperture 28 of the end 27. By now turning the screw the rim will be drawn toward the body. In the first movement of the rim following the hooking engagement at its top, the swinging movement toward the body will bring the edge 32 of the rim into engagement with the glass 15. Continued movement will gradually bring the entire edge 32 into engagement 10 with the glass and simultaneously cause flexure of the end 23 of the fastener 22 toward the front of the lamp. This yielding action of the top element will prevent unequal pressure being brought upon the glass. 15 When the screw 30 has been brought up tight at the bottom of the lamp the element at this point will function in the same manner as does the top one. Thus equal glass pressure is assured throughout its periphery, 20 hence preventing glass breakage.

The form of closure shown in Figs. 5 to 7 inclusive is quite similar to that described in Figs. 1 to 4 inclusive, in that it is identical except for the provision of an extension 32 from the reflector holding end 26. This extension 32 is provided with a lip 33 which aids the extension to function as a glass retaining clip as shown in Figs. 5 and 6. In the operation of securing a glass in 25 position the extension or clip is flexed to allow it to be released over the glass when it has been placed in position as shown. Incidentally the function of holding the reflector is performed as in the previously described construction, in addition to that of holding the closure glass. In other respects the fastener is identical as to general shape 30 and performance, with that of the previously described construction and has the same reference numerals applied to the features which are in common with those of the form shown in Figs. 1 to 4 inclusive.

In the modification shown in Figs. 8, 9 and 10 the construction has been changed 45 to adapt it to a type of lamp construction in which the body is of the form having no inwardly extending annular flange, so that the reflector rim 13 sets into the body and rests upon suitably positioned shelves 34. 50 In this case both ends of a substantially U-shaped fastener 40 at the top of the lamp body are located in and extend to the outside of a slot 35 formed near the edge of the body. One end 36 extends rearwardly for 55 engagement with the turned over hooked rear edge 37 of the closure rim, while the other end is divided into three tongues 41, 42 and 43, the tongues 41 and 42 being located in fastener supporting position against 60 the opposite wall of slot 35 from that engaged by end 36. The remaining tongue 43 is somewhat hooked and extends forwardly for reflector retaining engagement with the notch 44 of the reflector. At the bottom of 65 the lamp a fastener of somewhat different

appearance is provided. Extending from the closure rim is a lug 45 having a pivoted latch 46 secured thereto. An aperture 47 in the latch is adapted for closure fastening engagement with a spring lug 48 extending 70 from the body, the end of the lug having a hump 49 for retaining the latch in place. The operation of the construction just described is quite similar to that of the other constructions set forth herein and especially 75 to the form shown in Figs. 1 to 4 inclusive. For this reason the operation of such features as embody slight distinctions of construction, are self evident and need not be specifically described herein. 80

Having thus described my invention what I claim is:

1. A closure fastener for automobile lamps consisting of a body, a reflector located in the body, and a closure for the body and reflector, comprising two yielding elements located at substantially diametrically opposite sides of the lamp, each of said elements being located within the lamp body and having its ends occupying body slots, one end of each element occupying a slot located at the edge of the reflector flange and adapted to engage the reflector flange yieldingly, whereby the reflector will be retained in position relatively to the body, the other end of one element occupying a slot located adjacent to the rear edge of the closure and adapted to engage the rear edge of the closure, the other end of the cooperating element occupying a slot adjacent to the rear edge of the closure, and means adapted detachably to attach the closure to said end. 90

2. In combination in an automobile lamp consisting of a body having an open end, a reflector located within the body and supported at the open body end, and a closure mounted on the body and closing the reflector, a closure fastening element located at the top and another closure fastening element located at the bottom of the lamp, said top element being located within the lamp body and having its ends mounted in body slots, one of said ends being adapted to be placed in retaining engagement with the closure, the slot in which said closure retaining end is mounted having a tongue therein adapted for cooperative engagement with the end to prevent fastener displacement at any time, the bottom fastener having identical mounting conditions, and means adapted detachably to bring the bottom fastener into retaining relation with the closure. 100

3. In combination in an automobile lamp comprising a body having an inwardly flanged opening, an outwardly flanged reflector mounted in the body with the flanges of the body and reflector in supporting engagement with each other, and a closure upon the open end of the body adapted to 110

close the reflector and body, a closure fastener of substantially U-shaped formation mounted within the body with its ends occupying slots in the body, a similarly shaped fastener located in the body substantially diametrically opposite the first mentioned fastener and also having its ends occupying slots in the body, each of said fasteners having one end adapted yieldingly to engage 6 the reflector flange to prevent inadvertent displacement thereof from the body flange, the other end of each of said fasteners being 10

arranged for closure fastening relation with the body, one of said ends being arranged for direct attachment to the closure, the 15 other of said ends extending adjacent to the closure, and means adapted detachably to connect the closure with the other of said mentioned ends, whereby the closure will be supported yieldingly on the body. 20

In testimony whereof I have hereunto affixed my signature.

EUGENE A. KUEN.
